FISH SCALER

Lonnie G. Albright, Jr., 209 Lake Jeanette Road,
Greensboro, N.C. 27405

Filed Mar. 30, 1972, Ser. No. 239,844

Term of patent 14 years

Int. Cl. D7—04

U.S. Cl. D7—99

FIG. 1

FIG. 2

FIG. 3

FIG. 4

FIG. 1 is a top plan view of a fish scaler illustrating the concave surface of the blade, the bottom plan view being substantially identical thereto with the blade surface being convex;

FIG. 2 is a side elevational view of the fish scaler of FIG. 1;

FIG. 3 is an end elevational view of the fish scaler taken from the left side of FIG. 2; and

FIG. 4 is a perspective view of the fish scaler.

I claim:

The ornamental design for a fish scaler, as shown and described.
